SHOE SEWING MACHINE

Thomas Aubrey Kestell, Leicester, England, assignor to United Shoe Machinery Corporation, Flemington, N. J., a corporation of New Jersey

Application February 21, 1941, Serial No. 380,020
In Great Britain March 6, 1940

15 Claims. (Cl. 112—60)

The present invention relates to improvements in sewing machines. More particularly, the invention relates to a presser foot and its actuating mechanism for a machine of the type adapted for sewing a sole to a shoe bottom by a seam passing through the sole to the inside of the shoe. By way of illustrative example, the present invention is hereinafter described as embodied in a shoe sole sewing machine of the particular construction described in an application for U. S. Letters Patent to Gouldbourn and the present inventor Serial No. 274,794, filed May 20, 1939, which machine is a lockstitch sewing machine of the McKay type having a rotary shoe supporting horn for a work support.

One object of the present invention is to provide a novel presser foot mechanism for a shoe sole sewing machine having a rotary shoe supporting horn which is intended to control and hold the work in a more satisfactory manner on the horn than hitherto.

A shoe sole sewing machine of the type referred to usually is provided with a rotary shoe supporting horn which has in its upper end a needle threading whirl and with a hooked needle which passes through the work and enters an opening in the upper end of the horn to enable the needle thread to be wrapped around the needle by the whirl and also with a work feeding awl or feed point which penetrates and feeds the perforation thus formed in the work into line with the needle. Such machines also usually are provided with a presser foot arranged to hold the work on the horn except when the work is being fed to the needle and the presser foot usually is arranged at the side of the awl or feed point most remote from the needle, i. e., on the side of the awl or feed point from which the work is fed to the needle. As hereinafter referred to, the term "awl" will be assumed to indicate any work engaging device for similar purposes including a feed point.

In the illustrative mechanism hereinafter described as embodying the present invention, the presser foot is arranged to engage the work between the paths of movement of the awl and needle towards the work instead of at the same side of the needle and awl and the presser foot preferably is arranged to be moved out of the way of the awl as the latter feeds the work to the needle. With this arrangement, in the case of a McKay type machine, the presser foot is positioned directly above the work supporting face of the rotary horn close to the path of movement of the needle and also close to the path of

movement of the awl, both the needle and awl operating from the same side of the work.

This position of the presser foot ensures that the work is held down firmly on the horn close to the sewing point and prevents undesired upward movement of the work away from the horn which might be caused by upward movement of the awl or the needle as either is being withdrawn from the work as sometimes occurs if the presser foot engages the work at the opposite side of the awl a substantial distance from the needle. Further a presser foot so arranged is in a very convenient position to guide the work towards the needle and to control the thread measuring mechanism of the machine.

The above and other objects and the several features of the present invention will be apparent to those skilled in the art from the following specification, claims and drawings of the said illustrative presser foot mechanism and of its application to the particular lockstitch shoe sole sewing machine aforesaid.

In the drawings, Fig. 1 is a right-hand side elevation of part of a shoe sole sewing machine having embodied therein the illustrative presser foot mechanism; Fig. 2 is a front elevation of some of the parts shown in Fig. 1; Fig. 3 is a plan view, partly in section, of a presser foot of the illustrative mechanism and a needle, awl and part of a work supporting horn of the machine; Fig. 4 shows some of the parts shown in Fig. 1 during work feed by the awl; Figs. 5, 6 and 7 illustrate in front elevation, plan and side elevation, respectively, an alternative presser foot, indicating its relation to the horn in the latter figure; and Fig. 8 is a diagram illustrating the relative timing, in a machine cycle, of the awl, presser foot and presser foot lock.

The machine of the drawings is a shoe sewing machine of the McKay type for sewing shoe soles to uppers and insoles by through and through stitches and is provided with presser foot mechanism and a work support. In the presser foot mechanism of the illustrated machine, the upper end of a presser foot 1 is secured on the lower end of a presser bar 3, similar to the presser bar referred to as presser foot bar 249 in the Gouldbourn application referred to. The bar is supported by the forward ends of a pair of parallel arms 5 and 7, similar to the arms 251, 253 in said application. The presser foot acts to secure the work by clamping it against the work support in the form of a rotary shoe supporting horn 8. The present presser foot 1 is secured to the presser bar by a screw 9 and slot

connection which allows the presser foot to be adjusted horizontally laterally of the machine.

The presser foot 1, according to a feature of the present invention, extends downwardly and to the left from its upper end (viewing the machine from the front), in front of the path of downward movement of a four-motion work feeding awl 11 and at its lower work engaging end the presser foot has a rearwardly extending portion 13. The awl, during its feeding movement, moves into a position of alignment with the path of the needle, indicated at 15, as in the machine of the application. The rearwardly extending portion 13, when viewed from above, is positioned between the path of downward movement of the awl 11 while forming a perforation in the work and the path of downward movement of the needle 15 while entering into the perforation formed by the awl, the work engaging paths of the needle and awl being separated by a stitch length (see Fig. 2). The rearwardly extending portion 13 is about one-sixteenth of an inch thick, when viewed from above, and is about one-quarter of an inch high, its lower edge extending upwardly and forwardly. The lowest work engaging portion of the rearwardly extending portion 13 engages the work along the feed line which marks the path of awl movement during work feed and which passes through the stitch holes of the seam. The lower work engaging face of the presser foot has wings 14 and 29 at the sides of the portion 13. These wings are beveled slightly upwardly from the portion 13, as seen in Fig. 2, so that the work may be tipped slightly laterally of the machine and the presser foot in front of the portion 13 is beveled slightly upwardly and forwardly to permit the work to be tipped downwardly and rearwardly. The work engaging face of the portion 13 and the beveled wing faces are so arranged that more pressure is exerted on the work by the face on the portion 13 than by the beveled wing faces. The rear face 17 of the rearwardly extending portion extends upwardly and slightly rearwardly and is engaged by the inside face of a channel lip 19 on a shoe sole 21 which may conveniently be sewn to an upper 23 and insole 25.

By arranging the rearwardly extending portion 13 of the presser foot 1 between the paths of downward movement of the awl 11 and needle 15, the presser foot engages the work directly above the work supporting face of the work supporting horn 8 and close to the point where the awl 11 leaves the work and the needle 15 enters and leaves the work. The parts of the work which are being sewn together are therefore well pressed together at this point, thus assisting in the formation of tight stitching. This position of the rearwardly projecting portion 13 of the presser foot close to the awl and needle prevents the work from being lifted as the awl or needle are being raised and any tendency for the work to be bent upwardly slightly, as might occur if the presser foot which is holding the work down at this time is spaced as in previous machines of this type for instance, a half inch, away from the needle. Under these circumstances, the hole in the work would be enlarged slightly by the awl or needle, producing undesirable effects in the formation of the seam.

In the machine described in the Gouldbourn application, thread measuring means is provided for measuring off from a thread supply a length of thread for each stitch and the thread measuring means is controlled by the heightwise posi-

tion of the presser foot so that the length of thread measured off for each stitch is determined by the thickness of the work where it is engaged by the presser foot. The positioning of the rearwardly extending portion 13 of the presser foot close to the needle causes the thickness of the work to be measured close to the point where each stitch is being formed, helping to ensure a correct amount of thread to be measured off for each stitch.

The arrangement of the rearwardly extending portion 13 of the presser foot engaging the work along the line of feed enables the work to be tipped readily by the operator laterally and forwardly or rearwardly about the lower face of the presser foot without producing any undue tendency to raise the presser foot.

The presser foot wing 29 extending from the left lies at the front of and close to the needle path, and assists in holding the work firmly down on the horn 8.

To enable the work to be fed without obstructing the work feeding path of the awl during its movement along the seam line towards a position of alignment with the needle, the presser foot in the present machine is moved in a direction transverse to the seam line out of the awl feeding path in each sewing cycle. In the illustrative presser foot mechanism, the presser is raised and moved forwardly while the awl is feeding the work. After the awl has fed the work and before it is withdrawn therefrom, the presser foot is moved rearwardly and downwardly into engagement with the work to hold the work on the horn until just before the awl again commences to feed the work. Before the back-feeding movement of the awl starts, it is raised from the work sufficiently to clear portion 13 of the presser foot.

The presser bar 3 of the presser foot lifting mechanism is pivoted by a pin 31 to the arm 7 which is secured on a shaft 33 rotatably mounted in a head frame 35 of the machine and has also secured on it an arm 37. The arm 37 has pivotally connected to it a rod 39 which is pivotally connected at 41 to a pair of parallel short links 43, corresponding to the links referred to as the short links 265 in the Gouldbourn application. The short links 43 are pivotally connected at 45 to a rod 47 which is pivotally connected to an arm 49 corresponding to the arm referred to as the upwardly extending arm 275 in the application. The arm 49 is secured to a shaft 51, rotatably mounted in the head 35, which has secured to it an arm 53. The arm 53 carries a cam roll 55 which engages in a cam groove in the head 35, rotatably mounted in the shaft 51, corresponding to the shaft referred to as the horizontal crank shaft 29 in the application. The upper ends of the short links 43 are connected to locking mechanism similar to and operated by mechanism similar to that described in said application for locking the presser foot against upward movement.

The cam groove which is engaged by the roll 55 causes the presser foot to be raised to allow the work to be fed by the awl 11. The arm 5 is pivotally mounted on an eccentric portion 59 of a shaft 61 which is rotatably mounted in a bracket 63 secured to the head frame 35. The shaft 61 has secured on it, by a clamp screw 65, an arm 67 to which is pivotally connected by a stud 69 one end of a link 71. The other end of the link 71 is pivotally connected by a stud 73 to an arm 75 of a bell crank lever 77 which is

pivotedly mounted on a spindle 79 in the head 35. Another arm 81 of the bell crank lever 77 carries a cam roll 83 which engages a cam groove in a cam secured on the shaft 57.

When the bell crank lever 77 is rotated in a clockwise direction, as seen in Fig. 1, the eccentric portion 59 of the shaft 61 is moved forwardly and, through the arm 5, moves the presser foot forwardly parallel to the surface of the work about the axis of the pin 31 in the arm 7. This forward movement of the presser foot parallel to the surface of the work occurs during its upward lifting movement and when the presser foot is raised to allow the work to be fed by the awl, its projection 13 is moved so far forwardly that the awl can pass behind the projection.

To adjust the forward movement of the presser foot, the stud 73 is secured in an arcuate slot 85 in the arm 75, movement of the stud along the slot causing variation in the extent of forward movement. The arcuate slot is substantially concentric to the axis of the stud 69 when the presser foot is resting on work of medium thickness so that adjustment of the stud 73 along the slot 85 does not materially affect the position forwardly or rearwardly of the presser foot when it is in engagement with the work.

In the machine described in the Gouldbourn et al. application referred to, the presser foot is at the right-hand side of the awl, from which side the work is fed, and holds up and prevents the channel lip of a sole which is being sewn to a shoe bottom from being pierced by the awl. In the illustrative mechanism, however, the presser foot is at the left-hand side of the awl and the channel lip approaches the awl before it reaches the presser foot so that the channel lip is unsupported by the presser foot before it reaches the awl and may, if it is thin and flimsy, turn down into the path of the awl with the result that a few stitches may be formed, before the machine can be stopped, which stitches may pass through the channel lip, spoiling the work. Further, if a sole which is to be sewn to an upper and insole by the machine has had formed on it a flap, which later will be secured to the breast face of a heel on the shoe, and the flap and channel overlap, the overlapping portion of the flap which is usually thin might be pierced by the awl and sewn to the sole. To prevent the channel lip or flap from being pierced by the awl when the machine is operating on work having a thin flimsy channel lip or flap as aforesaid, the presser foot 1 has secured on it a rearwardly extending member 87 which is arranged to raise the channel lip or flap at the right of the awl path and hold the channel lip or flap up out of the way of the awl. With such a member, the awl during its work penetrating stroke passes down between the presser foot and the member.

The relative timing, in a machine cycle, of the movements of the awl towards and from the work, of the presser foot, presser lock and of the work feeding movement of the awl will now be described.

Assuming the machine to be in operation to sew a seam and the parts to have reached once more the positions which they occupied when the machine came to rest, the awl (see line A, Fig. 8) after having entered and fed the work in the previous cycle, will have fully risen away from the work and will have moved part way down again towards the work. The presser foot will be resting on the work and will be in its rearward position and will be locked against

upward movement. The awl continues to descend and in doing so enters the work without quite penetrating it and reaches its lowest position when the shaft 57 has rotated through about 45°. The awl remains more or less in its lowered position while the shaft 57 rotates through about a further 90° and then commences to rise, reaching its fully raised position when the shaft 57 has rotated through about 220° from its starting position. The awl remains in its fully raised position, except for a slight dipping movement, until the shaft 57 has rotated through about 335° from its starting position when it begins to move down again.

The awl (see line B in Fig. 8) commences to feed the work when the shaft 57 has rotated through about 65° from its starting position and feeds the work while the shaft 57 rotates through about a further 70°. The awl then dwells while the shaft 57 is rotating through about 35°, during which the awl is moving upwardly out of the work and the awl then commences to move in the opposite direction to that in which it feeds the work and continues to so move while the shaft 57 rotates through about 45°, the awl then remaining stationary, as far as its feeding and return movements are concerned, until the end of the cycle.

The presser foot (see line C in Fig. 8) is in its rearward position at the beginning of the machine cycle and commences to be moved forwardly when the shaft 57 has rotated through about 60° from its starting position. The presser foot is moved forwardly during about 30° of rotation of the shaft 57 and remains in its fully forward position during about 15° of rotation of the shaft 57. The presser foot is then moved rearwardly and reaches its rearward position when the shaft 57 has rotated through about a further 30° and remains in its rearward position until the end of the cycle.

The presser foot (see line D in Fig. 8) is down and in its rearward position on the work at the beginning of the machine cycle. The presser foot may, as described in said Gouldbourn et al. application, be raised slightly during about the first 40° of rotation of the shaft 57. When the shaft 57 has rotated through about 40°, the presser foot commences to be raised and is fully raised when the shaft 57 has rotated through a further 40°. The presser foot remains in its fully raised position while the shaft 57 rotates through about 40° and is then moved down towards the work by its cam and unlocked so that it is moved by spring means against the work, the presser foot remaining on the work until the end of the cycle.

It will be apparent that the presser foot is raised somewhat, during about 20° of rotation of the shaft 57, before it begins to be swung forwardly and this allows the presser foot to be lifted clear of the work before it is moved forwardly. Further, it will be apparent that the presser foot is moved rearwardly, during about 15 degrees of rotation of the shaft 57, before it is moved downwardly and this ensures that there will be no rearward movement of the presser foot after it engages the work. During about 30° of rotation of the shaft 57, the presser foot is moved upwardly and forwardly after it has been raised from the work and the presser foot is moved during this movement in a curved path extending upwardly and forwardly until it lies forward of the path of feeding movement of the awl which commences before the presser foot

reaches its most forward and fully raised position but is reached before the awl passes behind the rearwardly extending portion 13 of the presser foot. During its inward and downward movement, the presser first moves inward without moving downward during about 15° of rotation of the shaft 57, then moves both inward and downward during about 15° of rotation of the shaft 57 and then moves downward without being moved inward during about a further 15° of rotation of the shaft 57.

The return back feeding movement of the awl after it has fed the work takes place after the presser foot has been moved downwardly and rearwardly into engagement with the work, but since the awl is raised above the work during its return movement, it passes above the rearwardly projecting portion 13 of the presser foot.

The presser foot (see line E in Fig. 8) is locked against upward movement at the commencement of the machine cycle and remains so locked while the shaft 57 rotates through about 125°. The presser foot is unlocked during part of its downward movement, so that it may be moved down by its spring and accommodate itself to the thickness of the work during about 30° of rotation of the shaft 57 and is then locked again until the end of the cycle.

The presser foot 89 shown in Figs. 5, 6 and 7 is of a somewhat simpler construction in that it does not have a portion similar to the wing 29 on the presser foot 1 and may conveniently be used instead of the presser foot 1 when work is being operated upon which requires to be tipped considerably during the sewing, the absence of the wing 29 allowing such tipping to be more readily effected. The presser foot 89 may, of course, have secured to it a member similar to the member 87.

The nature and scope of the invention having been indicated, and an embodiment of the several features of the invention having been specifically described, what is claimed is:

1. A shoe sewing machine having, in combination, stitch forming devices including a needle and an awl movable along separated paths towards engagement with the work, said awl being movable while engaging the work towards a position of alignment with the needle path to feed the work, a work support, and a presser foot having a work engaging end formed with a portion extending between the work engaging paths of the needle and awl to clamp the work against the work support.

2. A shoe sewing machine having, in combination, stitch forming devices including a needle and an awl movable along separated paths towards engagement with the work, said awl being movable while engaging the work towards a position of alignment with the needle path to feed the work, a work support, and a presser foot having a work engaging end formed with a portion extending between the work engaging paths of the needle and awl to clamp the work against the work support, said presser foot being arranged for movement out of the path of the awl during work feed.

3. A shoe sewing machine having, in combination, stitch forming devices including a needle and an awl movable along separated paths towards engagement with the work, said awl being movable while engaging the work towards a position of alignment with the needle path to feed the work, a work support, a presser foot having a work engaging end formed with a portion ex-

tending between the work engaging paths of the needle and awl to clamp the work against the work support, and mechanism for moving the presser foot out of the path of the awl while the work is being fed.

4. A shoe sewing machine having, in combination, stitch forming devices including a needle and an awl movable along separated paths towards engagement with the work, said awl being movable while engaging the work towards a position of alignment with the needle path to feed the work, a work support, a presser foot having a work engaging end formed with a portion extending between the work engaging paths of the needle and awl to clamp the work against the work support, and mechanism for moving the presser foot out of the path of the awl while the work is being fed and into engagement with the work before the awl is disengaged from the work.

5. A shoe sewing machine having, in combination, stitch forming devices including a needle and an awl movable along separated paths towards engagement with the work, said awl being movable while engaging the work towards a position of alignment with the needle path to feed the work, a work support, a presser foot, mechanism for lifting the presser foot from the work, and mechanism separate from the lifting mechanism for moving the presser foot parallel to the surface of the work during each stitch forming cycle.

6. A shoe sewing machine having, in combination, stitch forming devices including a needle and an awl movable along separated paths towards engagement with the work, said awl being movable while engaging the work towards a position of alignment with the needle path to feed the work, a work support, a presser foot, mechanism for lifting the presser foot from the work, mechanism for moving the presser foot parallel to the surface of the work transversely of the seam line while being lifted and for returning the presser foot to its starting position when brought into engagement with the work, and means separate from the lifting mechanism for adjusting the extent of movement parallel to the surface of the work.

7. A shoe sewing machine having, in combination, stitch forming devices including a needle and an awl movable along separated paths towards engagement with the work, said awl being movable while engaging the work towards a position of alignment with the needle path to feed the work, a work support, a presser foot having a work engaging end formed with a portion extending between the work engaging paths of the needle and awl, and a wing extending along the seam line in front of the needle path to clamp the work against the work support.

8. A shoe sewing machine having, in combination, stitch forming devices including a needle and an awl movable along separated paths towards engagement with the work, said awl being movable while engaging the work towards a position of alignment with the needle path to feed the work, a work support, a presser foot having a work engaging end formed with a portion extending between the work engaging paths of the needle and awl, and wings extending along the seam line in front of the needle and awl work engaging paths to clamp the work against the work support.

9. A shoe sewing machine having, in combination, stitch forming devices including a needle

and an awl movable along separated paths towards engagement with the work, said awl being movable while engaging the work towards a position of alignment with the needle path to feed the work, a work support, a presser foot having a work engaging end formed with a portion extending between the work engaging paths of the needle and awl to clamp the work against the work support, and a channel flap raising member on the presser foot at the side of the awl work engaging path along the line of feed opposite said extending portion of the presser foot.

10. A McKay type shoe sewing machine for inserting a seam in a channelled work piece beneath a seam covering flap having, in combination, stitch forming devices including a needle and an awl movable along separate paths at one side of the work towards and from engagement with the work, a rotary shoe supporting horn on the other side of the work, and a presser foot movable towards the work and parallel to the surface of the work transversely of the seam line to raise the channel flap before each work penetrating stroke of the awl.

11. A McKay type shoe sewing machine for inserting a seam in a channelled work piece beneath a seam covering flap having, in combination, stitch forming devices including a needle and an awl movable along separate paths at one side of the work towards and from engagement with the work along separate paths, a rotary shoe supporting horn on the other side of the work, and a presser foot movable towards the work and parallel to the surface of the work transversely of the seam line to raise the channel flap before each work penetrating stroke of the awl, said presser foot having a work engaging portion acting between the needle and the awl work engaging paths to clamp the work against the horn, and a channel flap raising member on the presser foot at the side of the awl work engaging path along the line of feed opposite said portion of the presser foot.

12. A shoe sewing machine having, in combination, stitch forming devices including a needle, a work support, a presser foot, a presser foot bar on which the presser foot is mounted, a pair of parallel arms on which the presser foot bar is supported for movement towards and from the

work support to clamp and release the work, and means for actuating one of the arms at right angles to the line of movement of the presser foot towards and from the work to cause the presser foot to be moved parallel to the surface of the work.

13. A shoe sewing machine having, in combination, stitch forming devices including a needle, a work support, a presser foot, a presser foot bar on which the presser foot is mounted, a pair of parallel arms on which the presser foot bar is supported for movement towards and from the work support to clamp and release the work, separate shafts on which the arms are mounted, an eccentric portion on one of the shafts, and mechanism for actuating the eccentric shaft portion to move the presser foot parallel to the surface of the work.

14. A shoe sewing machine having, in combination, stitch forming devices including a needle and an awl movable along separated paths towards engagement with the work, said awl being movable while engaging the work towards a position of alignment with the needle path to feed the work, a work support, a presser foot having a work engaging end formed with a portion extending between the work engaging paths of the needle and awl, a wing extending along the seam line in front of the needle path to clamp the work against the work support, and mechanism for moving the presser foot transversely of the seam line out of the path of the awl while the work is being fed.

15. A shoe sewing machine having, in combination, stitch forming devices including a needle and a four-motion work feeding awl, said awl being movable while engaging the work towards a position of alignment with the needle path, a work support, a presser foot having a work engaging end formed with a portion extending between the work engaging paths of the needle and awl to clamp the work against the work support, and mechanism for moving the presser foot out of the path of the awl while the work is being fed and into engagement with the work before the awl is disengaged, the awl passing above said extending portion of the presser foot during back feeding movement of the awl.
